CHARLES MAGERKURTH, OF LOS ANGELES, CALIFORNIA, ASSIGNOR OF TWENTY ONE-HUNDREDTHS TO HENRY STOVER, OF LOS ANGELES, CALIFORNIA.

RAILROAD-CROSSING.

1,260,693.

Specification of Letters Patent. Patented Mar. 26, 1918.

Application filed August 29, 1917. Serial No. 188,832.

To all whom it may concern:

Be it known that I, CHARLES MAGERKURTH, a citizen of Peru, residing at Los Angeles, in the county of Los Angeles and 5 State of California, have invented new and useful Improvements in Railroad-Crossings, of which the following is a specification.

This invention relates to a railway crossing and particularly pertains to a noiseless 10 track intersection.

The principal object of this invention is to provide a device for use at track intersections which will allow the railway cars to pass across the intersecting rails without 15 noise or jar as is common with tracks of ordinary construction.

Other objects will appear hereinafter.

The invention is illustrated, by way of example, in the accompanying drawings in 20 which:

Figure 1 is a view in plan illustrating a track intersection constructed according to the spirit of the present invention.

Fig. 2 is a fragmentary view in plan 25 illustrating an adjustment mechanism for the actuating racks.

Fig. 3 is a fragmentary view in perspective illustrating one corner of the track intersection and disclosing in detail the 30 elements of the device.

Fig. 4 is a fragmentary view in section and elevation disclosing the operating mechanism of the device, with parts broken away for the sake of convenience.

35 Referring more particularly to the drawings, 10 and 11 indicate parallel rails forming a track which intersects a track formed of rails 12 and 13. The intersecting rails are united within intersection blocks 14, 15, 40 16 and 17. Interposed between the blocks and forming continuations of the tracks are fixed rail sections 18, 19, 20 and 21, the rail sections 18 and 20 being in longitudinal alinement with the rails 10 and 11 and the 45 rail sections 19 and 21 being in longitudinal alinement with the rails 12 and 13. These rail sections do not, however, extend the entire distance between the rails, but terminate an equal distance at each end from

50 the intersection blocks. These spaces are provided to receive vertically movable rail sections 22. The movable sections 22 are each formed with vertically extending tongues 23 and 24 along their opposite edges. The tongue 23 is flush with the

outer face of its movable rail section and extends into a vertical groove 25, one of which is formed along each of the two inner faces of each intersection block. The tongues 24 are disposed down the center of 60 the opposite edges of the movable rail sections and are mounted to slide vertically within grooves 26 formed at each end of each fixed rail section. Thus it will be seen that the movable rail sections may have vertical movement in relation to the fixed rails, this movement being allowed to provide clearance for the flanges of car wheels passing along the tracks.

The vertically movable rail sections are 70 held in their normal uppermost positions by springs 27, one of which is provided for each section. These springs are formed with a hooked end portion 28 which engages a spring pin 29 extending outwardly 75 from the inner face of each movable section. The main leaf of the spring extends substantially horizontal and around a pivot pin 30 secured to the inner face of a stationary rail section. An adjusting shank 31 is here 80 shown as formed integral with the spring and extending downwardly therebeneath to be engaged by an adjusting screw 32 mounted within a fixed lug 33 upon the inner face of the stationary rail member. In this manner any desired tension may be given the spring to resist the pressure of vehicles passing across the track.

As particularly shown in Fig. 4, the movable rail sections, when in their normal 90 positions, form a space 34 beneath them. This space is provided for a swinging lock block 35 which is of a height corresponding to the width of the space and will thereby positively support the movable rail section 95 when swung into the space. This will maintain the rail face of the main rail, the movable rail, and the stationary rail in horizontal alinement.

The blocks 35 are secured upon vertical pivot bolts 36 which are secured to brackets 37. These brackets are fastened by suitable means to a sub-frame 38 here shown as of channel section and as providing a support for all of the stationary rail sections as well 100 as the ends of the main rails. Mounted upon the upper ends of the pivot bolts 36 are gears 39 and 40 by which the blocks are alternately swung beneath the adjacent movable rail sections. These gears are in mesh 105 110

with racks 41 and 42 formed at opposite ends of actuating bars 43. As will be seen in Fig. 1, the gears and racks engage each other in such a manner as to cause movement of one rack to swing a block beneath one movable rail section and movement of the opposite rack to swing the same block beneath the other movable rail section adjacent thereto. These racks are automatically operated by the movement of car wheels passing along the tracks. This operation is performed by a trip lever 44 pivotally secured to the inner face of the main rails and having its free end extending inwardly toward the intersection so that when the car wheel 45 rolls along the rail toward the intersection, the lever will be swung downwardly and will actuate a bell crank 46. This crank is mounted upon a pivot pin 47 on the side of the rail and connects with the end of one of the racks by means of a pivoted connecting link 48. It will be understood that but one of the trip levers is required upon each track and upon each side of the intersection. As here shown, these levers are connected with the opposite ends of the parallel actuating bars so that the mechanism will be operated when the car approaches from either side of the intersection.

The actuating bars 43 are slidably mounted within bearings 49 and 50 mounted along the inner faces of the stationary rail sections. These bars are split and are provided with a turn-buckle 51 by which they may be lengthened or shortened so that the blocks 35 will have proper movement in relation to the spaces 34 beneath the movable sections.

Another adjustment is also provided the actuating bars to hold all of the racks and pinions in positive engagement with each other. This consists of a fixed cam 52 mounted upon one of the supporting brackets 37 and adapted to bear against a pin 53 which is slidably mounted with a sleeve 54. This sleeve is formed integral with one of the blocks 35. A spring 55 is mounted within the bore of the pin 53. Thus, as the pin is moved along the cam, the double inclined faces of the cam will lock the block in its extreme positions.

In operation, the device is assembled as shown in Fig. 1 and mounted upon the base 38, after which the mechanism is suitably inclosed and the tracks are paved. Assuming that a car approaches the intersection from the left along tracks 12 and 13, in the direction as indicated by the arrow —a—, a front wheel of the car trucks will strike the trip lever 44 at the left side of the track. This lever will be depressed and will draw actuating bar 43^a in the direction of arrow —b—, thus causing the racks 41 and 42 of this bar to actuate their respective gears 39

and 40 and swing the blocks 35 under the movable rail sections 22 at each end of the stationary rail section 19. Simultaneously, actuating bar 43^b will be moved in the direction of the arrow —c—, 43^c in the direction 70 of the arrow —d—, and 43^d in the direction of the arrow —e—. This will cause the blocks 35 in the opposite corners of the intersection to swing beneath the movable rail sections 22 at the opposite ends of the stationary rail 21 and will also cause the trip lever 44 secured to rail 13 to be depressed. As the car advances, the rail flanges will encounter the unsupported movable rail sections 22 at the opposite ends of stationary 75 rail sections 18 and 20 and will depress them against the resistance of the springs 27. In this manner the obstructing rail sections will be yieldably held while the rail sections over which the wheels pass will be positively supported, thus allowing the wheels to pass across the intersection without noise. When a car comes along the rails 10 and 11, the action will be reversed and the blocks 35 swung beneath the movable rail sections at 90 the opposite ends of the stationary rails 18 and 20 leaving the obstructing sections free to yield under the action of the wheels.

It will thus be seen that the device here disclosed provides simple means for establishing continuous track-ways across track intersections and further provides means for eliminating obstruction of the car wheels by the intersecting rails.

While I have shown the preferred construction of my railroad crossing as now known to me, it will be understood that various changes in the combination, construction and arrangement of parts may be made by those skilled in the art without departing from the spirit of my invention as claimed.

I claim:

1. In a railroad crossing, parallel line rails, parallel cross line rails, intersection blocks connecting the line rails to the cross line rails, fixed rail sections between the intersection blocks; there being spaces between the ends of the fixed rails and the intersection blocks; movable sections mounted to reciprocate vertically in said spaces, springs for yieldingly holding the movable sections in their uppermost positions, swinging lock blocks adapted to engage under the movable sections and rigidly hold the movable sections in their uppermost positions, vertical pivot bolts upon which the swinging lock blocks are mounted, gears fixed upon the pivot bolts, racks meshing with the gears, actuating bars connected to the racks, and trip levers pivotally mounted and connected to the actuating bars; so that car wheels passing along the track will move the blocks from under the movable sections and allow the car wheel flanges to pass.

2. In a railroad crossing, parallel line rails, parallel cross line rails, intersection blocks connecting the line rails to the cross line rails, fixed rail sections between the intersection blocks; there being spaces between the ends of the fixed rails and the intersection blocks; movable sections mounted to reciprocate vertically in said spaces; there being tongue and groove connections between the movable sections, the intersection blocks, and the fixed rail sections; springs for yieldingly holding the movable sections in their uppermost positions, swinging lock blocks adapted to engage under the movable sections and rigidly hold the movable sections in their uppermost positions, vertical pivot bolts upon which the swinging lock blocks are mounted, gears fixed upon the pivot bolts, racks meshing with the gears, actuating bars connected to the racks, and trip levers pivotally mounted and connected to the actuating bars; so that car wheels passing along the track will move the blocks from under the movable sections and allow the car wheel flanges to pass. 15 20 25

In testimony whereof I have signed my name to this specification.

CHARLES MAGERKURTH.
